UNITED STATES PATENT OFFICE.

WILLIAM LUTHER BOGLE, OF COLUMBUS, MISSISSIPPI, ASSIGNOR OF THREE-FOURTHS TO HENRY LEE BOWLIN, OF COLUMBUS, MISSISSIPPI.

LAMP-BURNER.

SPECIFICATION forming part of Letters Patent No. 726,247, dated April 28, 1903.

Application filed March 10, 1902. Serial No. 97,551. (No model.)

To all whom it may concern:

Be it known that I, WILLIAM LUTHER BOGLE, a citizen of the United States, residing at Columbus, in the county of Lowndes and 5 State of Mississippi, have invented a new and useful Lamp-Burner, of which the following is a specification.

This invention has for its object the production of a lamp-burner wherein the lamp-chimney will be self-adjusting or self-adapting to the holding means, whereby the work of placing the chimney upon the burner is greatly simplified and the danger of breakage minimized.

15 Another object of the invention is the production of a burner containing certain novel features of construction, all as hereinafter shown and described, and specifically pointed out in the claims.

20 In the drawings illustrative of the invention, Figure 1 is a transverse sectional elevation. Fig. 2 is a perspective view of the burner with the "bell" member elevated. Fig. 3 is a detail view of a slightly-modified 25 form of looped spring.

The burner frame or shell is formed with an outwardly-extended flange 5 at its lower edge, a vertical portion 6 rising therefrom, and a horizontal portion 7 merging into the 30 vertical portion by a curved portion 8. At the center the shell is formed with an upwardly-rising dome 9, and surrounding this dome a short distance therefrom is an annular rib 10, whereby an annular channel is 35 formed around the dome, as shown. Depending centrally from the under side of the shell is a rib 11, having an annular channel near its lower part.

The wick-supporting portion 12 of the 40 burner is of the usual construction and is supported by the dome portion 9, as shown.

Formed radially through the rib 10 and portions 5, 6, 7, and 8 of the shell are recesses or open slots 13, in which flat spring members 14 engage, conforming substantially to the outline of the parts 6 and 7, but projecting beyond the outer surface of the vertical portion 6, as shown. The upper ends of the springs 14 extend into the channel formed by 45 the rib 10 and the dome 9 and are secured to a ring 15, fitting this channel and supported 50

thereby, as shown. The lower ends of the springs 14 are extended inward beneath the frame and engaged by a ring 17, which is supported in the channel in the rib 11. By this 55 means the springs are securely supported upon the frame at both their upper and lower ends. The springs may each be constructed of a single piece bent to the proper shape (see Fig. 1) or in two parts united, as by riveting 60 at 18, (see Fig. 3,) as preferred.

The flame-protecting bell is of the usual construction and is represented at 19 and secured to the shell just outside the rib 10, which forms the support for the bell, as 65 shown.

The chimney is of the usual structure and is represented at 20 and will be engaged by the springs 14 and by the vertical portion 6 of the frame or shell. 70

The vertical portion 6 of the shell or frame, with the rounded upper portion 8 whereby the portion 6 is merged into the horizontal portion 7, is an important feature of the invention, as it enables the chimney to be placed 75 in position upon the burner without the necessity of adjusting it to the holding means, as in ordinary burners, as the chimney will readily adapt itself to the rounded form of the shell and will not be affected by any protruding portions of the holding means, as the ends of the holding-springs are entirely enclosed beneath the ring 15. Thus in placing the chimney upon the burner no care need be taken to locate or adjust it, as it will find 80 its own seat upon the flange 5 and will require the use of but one hand to engage it. On the other hand, the part comprising the chimney-supporting shell or frame, being loosely mounted upon the part comprising the wick-supporting means, will enable the framework and the chimney carried thereby to be removed from the wick-supporting portion in 85 the same manner as with the ordinary burner. 90

The ring 15 will be of non-heat-conducting 95 material and will be comparatively large in cross-section, so that the surrounding material of the shell and the springs will be protected somewhat from the heat.

Having thus described my invention, what 100 I claim is—

1. In a lamp-burner, a shell or frame hav-

- ing a lateral chimney-supporting flange and an upwardly-contracted chimney-seating portion rising therefrom and provided with radial slots, and looped springs having spaced 5 fixed extremities, extending downwardly within said slots and having free intermediate portions.
2. In a lamp-burner, a shell or frame adapted to support the chimney and having a laterally-extended flange and horizontal top, a vertical side portion merging by curved lines into said horizontal top, and having radial recesses in said vertical portion, a ring concentrically disposed on said shell or frame and 10 springs connected to said ring and occupying said recesses, and affording a support to the chimney, substantially as described.
3. In a lamp-burner, a shell or frame adapted to support the chimney, a ring of heat-non-conducting material concentrically disposed 15
- upon said shell or frame, springs radially disposed upon said frame and attached to said ring and affording a support for the chimney, substantially as described.
4. In a lamp-burner, a shell or frame having 25 a laterally-extended flange and a horizontal top, a vertical side portion merging into said horizontal top, radial recesses in said side portion, a ring centrally disposed above said horizontal top, a ring centrally disposed beneath 30 said horizontal top, and springs connected at their ends to said rings and seated in said recesses, substantially as described.
- 20 In testimony that I claim the foregoing as my own I have hereto affixed my signature in 35 the presence of two witnesses.

WILLIAM LUTHER BOGLE.
